UNITED STATES PATENT OFFICE.

HALVOR O. HEM, OF KANSAS CITY, KANSAS.

HOOP SIZING AND FLARING MACHINE.

SPECIFICATION forming part of Letters Patent No. 629,444, dated July 25, 1899.

Application filed November 21, 1898. Serial No. 697,097. (No model.)

To all whom it may concern:

Be it known that I, HALVOR O. HEM, of 5
Kansas City, Wyandotte county, Kansas, have
invented certain new and useful Improve-
ments in Hoop Sizing and Flaring Machines,
of which the following is a specification.

My invention relates to a machine for siz-
ing and flaring hoops such as are used on bar-
rels; and my object is to provide a machine
10 of this character consisting, essentially, of a
frustum which is contracted to receive each
hoop and expanded to stretch it to a uniform
size and flare.

A further object is to provide said frustum
15 with adjustable gages to support the hoop,
fitted over the frustum in a horizontal posi-
tion at the desired elevation.

A still further object is to provide a ma-
chine of this character which is positive, re-
20 liable, and rapid in action and simple, strong,
and durable of construction.

To these purposes the invention consists
in certain novel and peculiar features of con-
struction and combinations of parts, as will
25 be hereinafter described and claimed, and in
order that it may be fully understood refer-
ence is to be had to the accompanying draw-
ings, in which—

Figure 1 represents a top plan view of a
30 hoop sizing and flaring machine embodying
my invention. Fig. 2 is a vertical section of
the same, taken on the line II II of Fig. 1.
Fig. 3 is a top plan view of a slightly-modi-
fied form of hoop sizing and flaring machine
35 embodying my invention. Fig. 4 is a verti-
cal section taken on the line IV IV of the
same. Fig. 5 is a detail perspective view of
one of the adjustable segments forming the
frustum of Figs. 3 and 4. Fig. 6 is a per-
40 spective view of one of the adjustable gages
for supporting the hoop at any desired eleva-
tion on the frustum.

In order to fully understand the reasons
why the hoops are not uniform in size and
45 flare, it will be necessary to explain how they
are made.

A straight piece of band-iron, of proper
length, has holes punched at both ends to re-
ceive rivets, the holes in all hoops of the same
50 size being the same distance apart. This
punctured band-iron is then run through the
flaring-machine, which is constructed of two

rollers held tightly but yieldingly together,
adjusting means being provided for holding
one end of the rollers more tightly together 55
than the other, so that when the band-iron
passes between them it is compressed on one
edge more than on the other, or, in other
words, one edge is stretched more than the
other, in order to flare the hoop. This action 60
of course stretches the hoop as a whole some-
what; but on account of the fact that the
pieces of band-iron differ in thickness and
are of different degrees of hardness some of
the pieces will stretch more than others and 65
when the hoops are riveted together they will
consequently be of different sizes. Now to
avoid the necessity of discarding the largest
hoops they are all made so that the largest
will fit and the smaller ones have to be 70
stretched, and this stretching is accomplished
by taking the hoop after it is riveted together
and driving it down over a cone until it is
of the required size and flare. My invention
is designed to provide an automatic means 75
for stretching and flaring these small-sized
hoops with greater rapidity and at less ex-
pense than the same work can be accomplished
by hand.

Referring now to the drawings in detail, 1 80
designates the top of a metallic table or frame,
the legs 2 of the same being secured to the floor
in any suitable manner. This top is provided
centrally with an upwardly-projecting tubular
guide 3 and with a depending portion 4, which, 85
in conjunction with the caps 6 and 7, forms
bearings for the parallel shafts 8 and 9, re-
spectively, the shaft 9 being located in axial
alinement with said tubular extension. The
shaft 8 projects outward beyond the side of the 90
table-top, and mounted thereon are fast and
loose pulleys 10 and 11. Upon the shaft, be-
neath the table, is a gear-pinion 12, meshing
with a gear-wheel 13 upon shaft 9, and mount-
ed also upon the last-named shaft is the eccen- 95
tric 14.

The expandible cone or frustum is composed
of plates or members 15, segmental in cross-
section, arranged in a circle around and con-
centrically of the tubular extension 3. Said 100
plates or members are pivoted at their lower
ends to swing radially toward or from said
tubular extension upon the bolts 16, mounted
in lugs 17, cast with and projecting upward

from the table-top. Said plates, near their upper ends, are provided centrally with the inwardly-projecting lugs 18, pivotally connected by the radial links 19 with the cap or collar 20, screwed or otherwise secured upon the upper end of the vertical rod 21, the latter extending down through the tubular guide extension 3 and being pivoted, as at 22, to the eccentric-strap 23, which once in each revolution of the shaft 9 elevates and lowers the cap 20 and through the instrumentality of the links 19 swings the segments inward and outward, thereby contracting and expanding the frustum or cone.

15 Each segment 15 is provided at its outer side and centrally with the longitudinal T-shaped groove 24, and fitting adjustably in said grooves are adjustable gage-supports, said supports consisting of the upright portion 25, fitting in said grooves, the horizontal T-shaped portion 26, projecting horizontally out through said grooves, and the set-screws 27, extending through arms 25 and impinging upon the segments 15 in order to secure 25 the gage-supports at the desired point.

In sizing and flaring the hoop the gages are first adjusted to the proper point to limit the downward movement of the hoop when dropped over the frustum when contracted—30 that is, when the eccentric has lifted the cap or collar 20 to its highest point, as shown in Fig. 2. The continued revolution of the shaft causes the eccentric to lower said cap and expand the frustum, as hereinbefore explained, 35 until the eccentric brings the cap to its lowest position, thereby stretching the hoop to a predetermined size and flare, as will be readily seen.

By employing the adjustable gages it is obvious that hoops varying considerably in diameter may be stretched upon the same frustum; but in order to make it possible for a single machine to stretch hoops of any reasonable size the frustum is made of double construction—that is to say, is provided with a second circular series of segmental plates 15^a, corresponding to the series 15 and concentrically surrounding the same, the proportion being such that the upper ends of plates 45 15^a shall just overlap the lower ends of plates 15, so that hoops just small enough to fit upon the upper or narrow portion of the inner frustum or hoops large enough to embrace the outer frustum near its base, as well as all intermediate sizes, may be sized and flared.

The plates 15^a, forming the outer frustum, of course surround the inner series concentrically and are preferably secured thereto at their lower ends by bolts 28. At their upper ends connecting-bolts 29 are employed to tie said plates the proper distance apart, said bolts extending through separating-sleeves 30, which prevent the plates from approaching each other—that is to say, by means of 60 the bolts 28 and bolts 29 and sleeves 30 the outer cone temporarily is formed rigid with the inner cone and the movement of the lat-

ter through the instrumentalities described is of course imparted to the former. Furthermore, the plates 15^a, forming the outer 70 frustum, are provided with longitudinal grooves 31, corresponding to grooves 24, and mounted therein are adjustable gage-supports 32 of the type already described.

In practice the fast pulley 10 is connected 75 by a belt (not shown) to a counter-shaft or other motive power, and the motion imparted to said pulley is transmitted through the medium of the gearing described to the eccentric, causing the frustum to alternately expand and contract. With each contraction a previously sized and flared hoop is removed and replaced by a new one, which is sized and flared by the following expansive movement, as will be readily understood.

In Figs. 3 to 5, inclusive, I have shown a slightly-modified construction, this construction consisting in the main in the employment of radially-sliding segmental plates instead of swinging plates. In this case the table 1^a is 90 provided with radial grooves 1^b and with a central tubular guide 3^a, extending downward instead of upward, as does guide 3 of Fig. 2.

33 designates a series of segmental plates 95 arranged in a circle to form a frustum, and 34 a series of blocks secured thereto or cast therewith and dovetailed, preferably, to slide radially in the grooves 1^b. These blocks, like the plates 15, are toggle-jointed to the reciprocating rod 21, extending up through the tubular guide through the medium of the links 19 and the collar 20, mounted upon said rod. In this case the collar is shown as adjustable upon the rod by means of the adjusting-nuts 35, the adjustment of the collar upon the rod obviously varying the expansive movement of the frustum, and thereby accommodating it to hoops of varying sizes. In this case also various-sized hoops may be 110 accommodated by fitting the gage-supports, in the shape of pins 36, in different holes 37 in the segmental plates 33, said pins being designed, like the gage-supports previously described, to limit the distance the hoop drops 115 down upon the frustum.

From the above description it will be apparent that I have produced a machine by which hoops which are irregular as to size or flare may be made uniform with extreme rapidity and with a greater degree of accuracy than is possible by hand, and it is to be understood that I reserve the right to make such changes in the detail construction, arrangement, proportion, or form of the parts as will 120 not be a departure from the spirit and scope or sacrifice any of the advantages of my invention.

Having thus described the invention, what I claim as new, and desire to secure by Letters 130 Patent, is—

In a hoop sizing and flaring machine, the combination of a series of segmental plates arranged to form a cone, a reciprocating rod

arranged axially of said cone, links connecting the rod with the plates to cause the alternate contraction and expansion of the cone, and gage-plates mounted upon the segmental plates and adjustable longitudinally thereof to accommodate hoops of varying size, substantially as described.

In testimony whereof I affix my signature in the presence of two witnesses.

HALVOR O. HEM.
